[57] CLAIM

The ornamental design for a hand microphone, as shown and described.

DESCRIPTION

FIG. 1 is a front, top and right side perspective view of a hand microphone showing my new design, with the broken line cord fragment included for purposes of illustration only and forming no part of the claimed design;

FIG. 2 is a top plan view;

FIG. 3 is a left side elevational view;

FIG. 4 is a bottom plan view;

FIG. 5 is a front elevational view; and

FIG. 6 is a rear elevational view.

FIG. 1.

FIG. 5.

FIG. 6.

FIG. 2.

FIG. 3.

FIG. 4.
